UNITED STATES PATENT OFFICE.

ALBERT NAPOLEON TUCKER, OF GERRADS CROSS, ENGLAND.

MEANS OR DEVICE FOR ADAPTING SPORTING GUNS OR LIKE SMALL ARMS FOR
MINIATURE AMMUNITION PRACTICE OR USE.

Application filed June 27, 1921. Serial No. 480,927.

To all whom it may concern:

Be it known that ALBERT NAPOLEON TUCKER, a subject of the Kingdom of Great Britain, residing at Littlehaye, Bulstrode 5 Way, Gerrads Cross, in the county of Buckinghamshire, England, has invented an Improved Means or Device for Adapting Sporting Guns or like Small Arms for Miniature Ammunition Practice or Use, of 10 which the following is a specification.

The present invention has relation to an improved means or device for adapting sporting guns or like small arms for miniature ammunition practice or use, and has for 15 its object to enable an ordinary sporting or like gun to be so adapted that same may be employed for carrying out loading, arming and firing practice at a reduced range with a correspondingly reduced scatter or 20 separation of the pellets whereby correctness of aim may be tested conveniently against either a stationary or a small moving target in the open or in a small shed, room or the like. A suitable moving target 25 is described in my concurrent application.

According to the present invention an adaptor sleeve or tube is adapted to be positioned or disposed within the barrel of the gun by means of an integral flange or bearing part provided upon the sleeve or tube which bears against or contacts the bore of the barrel and a conical or equivalent nut working on a screw threaded part of the sleeve which bears against the coned part 30 of the barrel to position the sleeve or tube within the said barrel. A miniature cartridge is carried or supported in the cartridge chamber in axial alignment with the sleeve or tube and to the rear thereof by means of a 35 metal bouche or annulus contained within a liner or adaptor cartridge adapted to be slid into the cartridge chamber of the barrel. The sleeve or tube may be adjusted axially of the barrel by rotating same within the 40 said barrel in relation to the fixed conical nut aforesaid.

In order that this invention may be clearly understood and readily carried into practice, reference may be had to the appended explanatory sheet of drawings upon which:—

Figure 1 is a longitudinal section taken through the cartridge chamber extremity of the barrel of a sporting gun illustrating

the present adapting device or means and cartridge provision in position. 55

Figure 2 is a transverse section taken on line *a a* of Figure 1.

In a convenient embodiment of the present invention the adaptor sleeve or tube 1 is provided at its foremost extremity with 60 a flange 2 which frictionally engages or slides within the uniform bore 3 of the barrel 4 of the gun. This adaptor sleeve or tube 1 is screw threaded and thickened towards its rear extremity at 5 and a conical nut 6 is adapted to work upon said screw threaded part and co-operate with the coned part 7 of the barrel between the cartridge chamber 8 and the uniform bore 3. The rear extremity of the adaptor sleeve or 65 tube 1 is provided with an enlarged or flared opening 9 and flat faces 10 or like provision for enabling the member 1 to be rotated within the barrel by means of a suitable female tool which engages the faces 10. In order to position this adaptor sleeve or tube the conical nut is screwed or moved to the foremost extremity of the sleeve or tube 70 adjacent the flange 1 and the said sleeve or tube 1 is slidingly engaged with the barrel. The conical nut 6 is then securely jammed within the conical part 7 conveniently with a special tool. The sleeve or tube 1 is then 75 adjusted axially within the barrel by means of the female tool by rotation of the said sleeve or tube in relation to the fixed conical nut 6. A strip may be provided upon the female tool adaptor to contact the breech of the barrel when the adaptor tube or sleeve 1 has been screwed sufficiently far into the 80 barrel.

In order to form a suitable chamber for the miniature cartridge 11 a liner or adaptor cartridge 12 is employed of similar dimensions to the full sized cartridge for 85 which the barrel is constructed, said liner or adaptor cartridge 12 is provided internally with a metal bouche or annulus 13 which may be rigidly positioned within the liner 12 by pressing small parts 14 into recesses in the metal bouche or annulus by means of a punch or like instrument. The bouche or annulus 13 is also provided with a wire or other suitable spring 15 adapted to project into the miniature cartridge 90 chamber, so as to normally bear against the 100

miniature cartridge 11 when same is in position. When the adaptor cartridge 12 and miniature cartridge 11 are in position in the breech the foremost extremity of the miniature cartridge projects into the enlarged or flared opening 9 aforementioned and the internal diameter of the cartridge 11 is preferably equal to the internal diameter of the adaptor sleeve or tube 1.

With the present device it will be seen that the adaptor sleeve or tube may be securely positioned in the barrel of a sporting or like gun and loading, aiming and firing practice may be carried on under the same conditions as when employing the full sized cartridges for which the gun is adapted. By axially adjusting the sleeve or tube 1 as aforesaid same may be disposed or mounted in any gun so that the enlarged or flared opening 9 always covers or engages the foremost extremity of the miniature cartridge 11.

The miniature cartridge 11 may be centrally fired and provided with a substantially thick shell in order that it may resist the initial explosion without distortion and also admit of continuous reloading or refilling. The detonating cap, chamber and anvil 16 may be similar to those in universal use in ordinary sporting cartridges. The loading of the cartridge 11 may be varied as to powder and wadding to suit the requirement of the shooter. According to one suitable loading four grains of fine black

powder, a quarter inch felt wad, glazed paper wad, about 300 pellets and a close fitting paper wad on top, may be employed.

In loading the gun the only deviation from ordinary manipulation is that the miniature cartridge 11 has to be first inserted into the liner or adaptor cartridge 12 but this can obviously be done before the practice commences.

What I claim as my invention, and desire to secure by Letters Patent is:—

1. An adaptor device for use in sporting guns and like small arms comprising a sleeve arranged to be positioned within the barrel of the gun and having a fixed flange at its front end arranged to engage in the plain portion of the bore of the barrel, and a frusto-conical nut threaded on the rear portion of the sleeve and arranged to bear against the coned part of the barrel to position the sleeve.

2. In combination with an adaptor device as claimed in claim 1, an adaptor cartridge for the reception of a sub-calibre cartridge and comprising a shell to fit in the breach chamber of the barrel, an annulus in said shell having a sub-calibre bore, and a spring in said annulus to bear against a subcalibre cartridge in the bore of said annulus.

In witness whereof I have hereunto set my hand.

ALBERT NAPOLEON TUCKER.
